UNITED STATES PATENT OFFICE

CARL E. TIDEMAN, OF WORCESTER, MASSACHUSETTS, ASSIGNOR TO BURLINGAME MACHINE COMPANY, OF WORCESTER, MASSACHUSETTS, A CORPORATION OF MASSACHUSETTS

WIRE-DRAWING MACHINE

Application filed May 25, 1927. Serial No. 194,198.

This invention relates to a machine for drawing wire through a series of dies continuously. The principal objects of the invention are to provide improved driving means for the machine in which the drawing through drum is driven positively and the winding drum is driven in such a way that it can be stopped independently of the drawing through drum; to provide a machine in which the horizontal and vertical types are combined; to provide an improved location of the respective parts of the machine so as to provide the necessary parts in a comparatively small space, and to provide other improvements and advantages which will be described below.

Reference is to be had to the accompanying drawings in which

Fig. 1 is a plan of a wire drawing machine constructed in accordance with this invention;

Fig. 2 is a side view; and

Fig. 3 is an end view with the means for driving the winding drum in section.

The machine is shown as mounted upon a frame 10 which has a horizontal driving shaft 11 driven through a pulley 12. This shaft is provided with a pulley 13 fixed thereon, which, by a belt 14 passing over idlers drives a pulley 15 on a vertical shaft 16. This shaft 16 is in two parts adapted to be connected and disconnected by a clutch 17 operated by a handle 18. To the upper part of the shaft 16 is secured the hub of the winding drum 20. The shaft has a bearing in the frame and is supported on the top of this bearing by a collar. It also has a collar below to prevent vertical vibration.

On the shaft 11 is a clutch 25 which connects it with a shaft 26 in line with it on which is a gear 27 driving a horizontal parallel shaft 28 through another gear. On this shaft is the solid conical drawing through drum 29 which is provided with a series of grooves in the usual way for drawing the wire. It is driven positively from the shaft 11 when the clutch is in. The clutch is operated by a handle 30.

Supported on the side of the frame over a trough 31 for the cooling solution is a conical

idler drum made up of a series of grooved discs 32 and separating plates 33. These are mounted to turn freely on a horizontal shaft 34 which is supported on bearings on the frame 10 like the shaft 28. These discs are made loose and the entire drawing action is secured from the positively driven drum 29.

A die holder 36 is shown supported by the frame and located above the trough 31. Its wall has a series of passages for the wire behind which are located the dies 37. This trough has a series of partitions dividing it into compartments draining into one another as they are located at different levels.

Supported on the frame beyond the trough 31 is another die holder 39. This die holder can be used for holding a die whenever it is desired to draw wire dry, that is without the use of a solution.

On the shaft 11 is a sprocket driving a chain 40 which operates a pump 41 for conducting a solution through a pipe 42 and applying it to the wires through a perforated pipe 43 to which it extends. The solution is deposited on each wire in a stream while they are on the drum 29 or just as they are passing to it.

It will be seen that in the operation of the machine the single wire comes in from the left as shown in Fig. 1 and passes around one of the discs 32 and then is fed to the drum 29 around which it passes twice. Then it goes back around another disc 32. This operation is repeated over and over and the wire finally passes to the winding drum 20. The discs on the drum 32 are rotatable independently and are not rotated positively, while the drum 29 is in a single piece rotating positively. The drum 20, being operated through a belt, is not turned with absolute positiveness, although the effect is the same, except when there is too great strain. Furthermore this winding drum can be stopped when the wire is wound unevenly on it. The drum 29 continues to operate to take up any slack between the drums 29 and 32. In case of breakage, either drum 20 or 29 can be run without the other. Also the drum 20 can be operated by itself to take up slack if it occurs between the drum 29 and the winding drum. By hav-

ing the drums 29 and 32 rotate on horizontal axes and the drum 20 on a vertical axis, some of the advantages of the horizontal and vertical machines can be retained and the machine will occupy a minimum of floor space.

5 Although I have illustrated and described only a single form of the invention I am aware of the fact that modifications can be made therein by any person skilled in the art without departing from the scope of the invention 10 as expressed in the claims.

Therefore, I do not wish to be limited to the details of construction herein disclosed, but what I do claim is:

15 In a wire drawing machine, the combination with a drawing through drum and a winding drum, of a power shaft, positive means for driving the drawing through drum from the driving shaft, means for 20 disconnecting said positive means from the power shaft, belt driven means for driving the winding drum from the power shaft independently, and means for disconnecting the winding drum from the power shaft, so 25 that either the winding drum or the drawing through drum can be operated independently.

In testimony whereof I have hereunto affixed my signature.

CARL E. TIDEMAN.
